Inventor:
Sidney Born,
By Constantine,
his Atty.

UNITED STATES PATENT OFFICE.

SIDNEY BORN, OF BARTLESVILLE, OKLAHOMA.

PETROLEUM-DISTILLING APPARATUS.

1,284,124.

Specification of Letters Patent. Patented July 24, 1917.

Application filed January 25, 1917. Serial No. 144,427.

To all whom it may concern:

Be it known that I, SIDNEY BORN, a citizen of the United States, and a resident of the city of Bartlesville, in the county of Washington and State of Oklahoma, have invented a new and useful Improvement in Petroleum-Distilling Apparatus, of which the following is a specification.

My invention relates to an improvement 10 in the still of petroleum distilling apparatus, which I have devised more immediately for the apparatus employed in practising the process of distilling mineral oils and like products, set forth in United States Letters 15 Patent No. 419,931, granted January 21, 1890, to James Dewar and Boerton Redwood.

In commercially practising the aforesaid 20 and similar processes on a large scale, wherein the capacity of the still and the quantity of the material treated therein is several hundred barrels, it is found that the accumulation of carbon on the still bottom precludes continuing the run long enough to 25 convert into lighter hydrocarbons more than about one-fourth of the material contained in the still. This is because the carbon formed in the process is a good non-conductor and the still bottom under it becomes red 30 hot and, if the run were continued, would soon burn through the bottom of the still as well as retard the distillation itself.

The primary object of my invention is to 35 prolong the run to an extent that will enable say one-half, more or less, of the still contents to be converted into lighter hydrocarbons without incurring the objectionable results above referred to, and this I accomplish by the means illustrated in the accompanying drawing, in which—

Figure 1 is a longitudinal section through a still provided with my improvement; and

Fig. 2 is a transverse section of the same 45 on line 2—2 in Fig. 1. The same reference numbers are used to designate the same parts in both figures.

The still 3 is provided with the usual appurtenances of a still, such as a burner 4 for heating, a flue 5, a safety valve 6, a 50 vapor outlet 7, a pressure gage 8, a valved inlet pipe 9 for filling, a manhole 10 closed by a cover 11, a thermometer 12, and a drain cock 13. There is provided a chain 14, or series of chains, lying along the bottom and along the curved sides of the still

and covering approximately one-fourth of the total circumference. The chain may be either one continuous chain, looped at the ends in any suitable manner and the ends suspended free from the bottom by means of 60 suitable hooks 15 to enable the chain to be more easily removed, or it may be a number of individual chains fastened in any suitable manner.

In the operation of the still the liquid 65 hydrocarbon contents are heated to their boiling point by the heat from the furnace and circulate freely about and around the length of chain. The carbon which is produced by the breaking up or "cracking" of 70 the charge under the action of the heat, instead of depositing on the still bottom proper and causing the objectionable circumstances referred to above, forms, for the greater part, on the chains lying on the 75 bottom of the still. After the run has been completed, or whenever the accumulation of carbon renders it necessary, the still is opened, the ends of the chain are removed from the hooks and the chain is pulled out 80 of the still. In this way, most of the carbon adhering to the chain is removed with the chain, and the small amount adhering to the still bottom has been so broken up by 85 pulling out the chain that it can very readily be removed.

I realize that considerable variation is possible in the details of construction of the still and chains which I have specifically shown and described, and I do not intend 90 by illustrating a single specific or preferred embodiment of my invention to be limited thereto except as required by the limitations imposed in the following claim, it being my intention to claim protection upon all 95 the novelty there may be in my invention as broadly as the state of the art will permit.

I herein claim as my invention:

In an apparatus of the character described the combination with a still of parallel 100 lengths of chain lying upon and extending along the still bottom from end to end of the still to cover substantially its entire bottom, said still having an opening near its bottom through which said chain may be inserted and removed.

Signed at Bartlesville, Oklahoma, this 20th day of January, 1917.

SIDNEY BORN.
